[57] CLAIM

The ornamental design for a carton, substantially as shown and described.

DESCRIPTION

FIG. 1 is a front elevational view of a carton showing my new design, the rear being plain and unornamented; FIG. 2 is an elevational view looking from the right of FIG. 1;

FIG. 3 is an elevational view looking from the left of FIG. 1;

FIG. 4 is a top plan view; and

FIG. 5 is a bottom plan view thereof.

The drawing is shaded to show contrasting color.
